STOVE

Avery M. Cochran, United States Army,
Colorado Springs, Colo.

Application October 9, 1942, Serial No. 461,369

3 Claims. (Cl. 126—29)

(Granted under the act of March 3, 1883, as
amended April 30, 1928; 370 O. G. 757)

The invention described herein, if patented, may be manufactured and used by or for the Government for governmental purposes, without the payment to me of any royalty thereon.

The present invention relates to stoves, and more particularly to a novel form of camp stove suitable for military troops, or as a part of civilian camping equipment.

The principal object of the present invention is the provision of an extremely simple, light, and compact stove structure including a stove body, together with front and rear panels which may be easily attached to, or detached from, the body of the stove, and which are provided with separable braces or legs to give stability to the stove structure.

A further object of the invention is the provision of a pair of stove panel units of such design and construction that they may be combined with one or two ordinary 5-gallon metal gasoline cans of conventional design, in order to provide a stove structure, the arrangement being such that the front and rear panels are relatively flat and will occupy a minimum amount of space and so that a very satisfactory stove may be improvised by cutting the top and bottom from a standard shape fuel can and assembling the panel units at either end of the can so that the can body will act as the fire chamber of the stove, while the front and rear stove panels will provide adequate means for attachment of flues and a satisfactory fuel door.

A further object of the invention resides in the provision of a pair of front and rear panels adapted to be assembled at the opposite ends of a rectangular stove body, together with braces arranged to support the panels and to interlock the panels and the stove body.

Referring now more particularly to the drawing attached to and forming a part of the present specification:

Fig. 1 is a perspective view of an assembled stove constructed in accordance with the teachings of this disclosure;

Fig. 2 is a longitudinal sectional view through the stove illustrated in Fig. 1.

The body 11 of the stove consists of a relatively long, square sheet metal tube which in the preferred construction is of dimensions approximating 9 1/4 x 9 1/4 x 24" and which may be made by ordinary 20-gauge black iron, seamed along one side as illustrated at 12. It may be pointed out at this point of the application, however, that while this stove body portion 11 may be manufactured as a part of the assembly, yet it is one

of the main features of the present invention that the front and rear panels to be hereinafter described may be attached to any conventional type of square gasoline can; and, since such containers or gasoline cans are in wide use at the present time and easy to obtain in any locality, a set of panels may be sold as an article of commerce to be used in connection with a stove body portion obtained elsewhere. In this connection it may be pointed out that it has been common practice in some localities for many years to improvise stoves from fuel oil containers, usually from two 5-gallon gasoline tins telescoped into each other. Such improvised structures have been satisfactory within reasonable limits, but the present invention proposes to provide end panels so arranged that they may be easily attached to the opposite ends of a conventional type of fuel can and permanently secured thereto to provide a more neat, efficient and rugged stove, and to provide mechanically perfect flue mountings and fuel doors, and thus overcome the deficiencies of the so-called Yukon stoves heretofore known.

To this end the present invention provides a substantially square front panel 13 having deep side flanges 14, top flanges 15, and bottom flanges 16. The panel is provided with a hinged door 17 preferably mounted on hinges as illustrated at 18 and closed by a latch 19. The door 17 may also be provided with any desired type of draft control device, such as the pivoted door 21, arranged to close the draft door opening 22 in the door 17.

The upper flange 15 and lower flange 16 of the end panel are perforated at 23 and 24, respectively, to receive the opposite ends of a pair of stove legs or braces. Each of these includes a vertical riser portion 25, the lower end of which is joined to the stove panel by a horizontal rail portion 26 terminating in a vertical pin 27, which enters one of the lower openings 24 in the bottom flange 16 and extends upwardly through a registering opening 28 in the body 11 of the stove. The upper end of the riser portion 26 of each of the legs extends inwardly to provide a top rail 31 terminating in a downwardly extending pin 32 passing through the opening 23 in the top flange of the stove panel and through an opening 33 in the body portion 11 of the stove. The top rail 31 of the stove leg is formed to include a limiting stop 34 spaced apart from the pin 32 sufficiently so that it will bear against one of the side flanges 14 of the stove panel and prevent pivotal movement of the leg 25 about the pins 27 and 32.

From the foregoing it will be seen that the

panel may be secured to the stove by simply positioning the flanges 14 over the ends of the stove body 11, or by inserting the lower pin 27 through the registering openings 24 and 28, and then flexing the leg portions sufficiently to snap the upper pins 27 into position through the registering openings 23 and 33.

The panel may be similarly secured to a gasoline can by simply positioning the flanges 14 over the open end of the can, perforating the can by the use of any sharp instrument inserted through the openings 23 and 24, and locking the panel in position on the end of the gasoline container by inserting the lower pins 27, and snapping upper pins 27 into position through the openings 23 and 24 in the same manner as just described.

The rear panel 13a is of square shape, of the same dimensions as the front panel 13, and includes side flanges 14a, as well as a top flange 15a and bottom flange 16a, corresponding to and matching the flanges 14, 15, and 16 of the front panel. Similarly, it is provided with a pair of resilient rectangular wire legs 25a having lower rails 26a terminating in lower pins 27a, and top rails 31a terminating in top pins 32a, together with stop portions 34a which function in a manner identical to the stop portions 34.

The upwardly extending bottom pins 27a and downwardly extending top pins 32a pass through the openings 24a and 23a in the bottom flange 16a and top flange 15a of the rear panel 13a and through openings 28a and 33a in the body portion 11, to lock the stove panels and body together in the same manner as described, in connection with the front panel.

The rear panel 13a is provided with a flanged flue opening 38 to establish communication between the fire chamber of the stove and a flue pipe 37 extending to the stack 36.

As hereinbefore pointed out, the present invention provides a novel and useful collapsible stove structure that may be assembled simply by placing the opposite end panels 13 and 13a on the opposite ends of the body 11 and locking the entire assembly together by snapping the legs 25 and 25a into position so that the upper and lower pins of these legs pass through the registering openings in the stove body and panel flanges, and thus secure the entire stove in assembled position. Further, the panels 13 and 13a may be utilized without the body portion 11 to provide efficient flue mounting means and fuel door mechanism, and thus permit one or two ordinary square sheet metal gasoline containers to be improvised as a heating or cooking stove. This may be done merely by cutting out the ends of the gasoline container, perforating the sheet metal of the container, and locking the stove in assembled position.

Having thus described my invention, what I claim as new and desire to secure by Letters Patent is:

1. In a stove structure, in combination, a body portion comprising a relatively long, narrow rectangular sheet metal tube including perforations in its top and bottom walls adjacent each end of each of said walls; a pair of end panels for said stove body; each of said panels including a substantially square, flat plate having relatively deep flanges on the top, bottom, and both sides; the top and bottom flanges of each plate including

perforations adjacent the opposite side flanges thereof; stove legs attached to the opposite sides of each of said panels; each of said stove legs comprising a vertical riser portion spaced apart from the panel, top and bottom rails extending horizontally from the top and bottom of said riser to the top and bottom flanges of the panels respectively; said rails terminating in a downwardly extending top pin and an upwardly extending bottom pin respectively; said top and bottom pins adapted to extend through the perforations in the panels and through the aforementioned perforations in the body of the stove to secure the panels in position on said stove body, together with limiting stops for said legs, each stop consisting of a vertical projection on one of the aforementioned rails at a point adjacent one of said pins; the limiting stops contacting the flange of the end panel to prevent pivotal movement of the legs.

2. In a stove structure, in combination, a body portion comprising a single integral rectangular sheet of metal of uniform length and width, folded along four lines equally spaced from each other and having two of its opposite edges secured together to provide a relatively long, narrow rectangular sheet metal tube having its top, bottom, and both sides of integral construction and of equal length, said tube including perforations in its top and bottom walls adjacent each end of each of said walls; a pair of end panels for said stove body; each of said panels including a substantially square, flat plate having relatively deep flanges on the top, bottom, and both sides; the top and bottom flanges of each plate including perforations adjacent the opposite side flanges thereof; stove legs attached to the opposite sides of each of said panels; each of said stove legs including a support spaced apart from the panel, and including a downwardly extending top pin and an upwardly extending bottom pin; said top and bottom pins being adapted to extend through the perforations in the panels and through the aforementioned perforations in the body of the stove to secure the panels in position on said stove body.

3. As an article of manufacture, an end panel for a stove body; said panel including a substantially square, flat plate having relatively deep flanges on the top, bottom, and both sides; the top and bottom flanges of the plate including perforations adjacent the opposite side flanges thereof; stove legs attached to the opposite sides of said panel; each of said stove legs comprising a vertical riser portion spaced apart from the panel, top and bottom rails extending horizontally from the top and bottom of said riser to the top and bottom flanges of the panel, respectively; said rails terminating in a downwardly extending top pin and an upwardly extending bottom pin, respectively; said top and bottom pins being adapted to extend through the aforementioned perforations in the flanges of the panel to secure the panel in position on a stove body, together with limiting stops for said legs, each stop consisting of a vertical projection on one of the aforementioned rails at a point adjacent one of said pins; the limiting stops contacting the flange of the end panel to prevent pivotal movement of the legs.

AVERY M. COCHRAN.
